CLAIM

The ornamental design for a pipe inspection camera, as shown and described.

DESCRIPTION

FIG. 1 is a front perspective view of a pipe inspection camera, showing my new design;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof; and,
FIG. 8 is a bottom view thereof.

The broken lines in the drawings illustrate the portions of the pipe inspection camera, which form no part of the claimed design.
